(57) **CLAIM**

The ornamental design for a baby stroller forward frame, as shown and described.

DESCRIPTION

FIG. 1 is a front perspective view of a baby stroller forward frame showing our new design.

FIG. 2 is a top plan view thereof.

FIG. 3 is a front elevational view thereof, the rear elevational view thereof being a mirror image thereto.

FIG. 4 is a bottom plan view thereof; and,

FIG. 5 is a left side elevational view thereof, the right side elevational view being a mirror image thereto.

The broken lines are for illustrative purposes only and form no part of the claimed design.
